UNITED STATES PATENT OFFICE

159,892

PINKING MACHINE

Kaj S. Christensen, Norwalk, Conn., assignor, by
mesne assignments, to Samuel Briskman, New
York, N. Y.

Application June 18, 1949, Serial No. 3,386

Term of patent 14 years

(Cl. D22—5)

To all whom it may concern:

Be it known that I, Kaj S. Christensen, a citizen of the United States, residing at Norwalk, county of Fairfield, and State of Connecticut, have invented a new, original, and ornamental Design for a Pinking Machine, of which the following is a specification, reference being had to the accompanying drawing, forming part thereof.

Figure 1 is a perspective view of a pinking machine, showing my new design.

Fig. 2 is a side view thereof.

Fig. 3 is a front view thereof.

I claim:

The ornamental design for a pinking machine, as shown.

KAJ S. CHRISTENSEN.
